FOLDING AUXILIARY TRAY PROVIDED SEAT

Alfred Z. Boyajian, Farmingdale, N. Y.

Application September 17, 1949, Serial No. 116,336

15 Claims. (Cl. 155—127)

1

The present invention may be said to reside in a seat structure, embodying all of the functional features and characteristics of a high chair, to be removably and temporarily associated and employed in conjunction with a full size, conventional chair whereby an auxiliary seat is provided thereon particularly adapted for use by infants or children. Thus this auxiliary seat readily and easily enables the conversion of a full size or standard chair into a high chair, having all of the usual and customary appurtenances of such a chair, and permits of its reconversion to its original condition for normal or adult use without change in, or damage to, any of the parts or components thereof.

Among its other objects, the instant invention contemplates an auxiliary seat that may be collapsed or folded compactly into relatively small space for storage or transportation when not in use and the mere extension of which for use will automatically position and correlate all of its several elements or components for immediate association with a standard chair.

Another feature of the subject seat is its adaptation and adjustment to the child or infant occupying it thereby imparting flexibility in its use to the structure and improving the comfort of the occupant. Moreover this adaptation and adjustment of the seat tends to hold the occupant in place therein and reduces the hazards attendant on the use of the inflexible, non-adjustable high chair heretofore generally used.

With the above and other objects in view, as will be apparent, this invention consists in the construction, combination and arrangement of parts all as hereinafter more fully described, claimed and illustrated in the accompanying drawings, wherein:

Fig. 1 is a front elevation of an auxiliary seat constructed in accordance with the present invention showing it extended for use in conjunction with a standard chair;

Fig. 2 is a side elevation thereof showing it extended and mounted on a standard chair of the type commonly used in dining room or kitchen, the chair being shown in broken lines and an adjustment of the tray with reference to the back of the auxiliary seat being also illustrated in broken or phantom lines;

Fig. 3 is a plan view of the present auxiliary seat illustrating the tray thereof adjusted to the position shown in phantom lines in Fig. 2;

Fig. 4 is a side elevation of the auxiliary seat fully collapsed or folded for storage or transportation and shows it extended in phantom lines;

Fig. 5 is a bottom view of one of the adjustable arms which carry the tray showing the means by which the arm may be locked in a selected adjusted position;

2

Fig. 6 is a transverse section taken along line 6—6 of Fig. 2;

Fig. 7 is a transverse section taken along line 7—7 of Fig. 2;

Fig. 8 is a fragmentary vertical section, to larger scale, on line 8—8 of Fig. 2; and

Fig. 9 is a diagram, illustrating the operation of the parts.

Heretofore high-chairs, used for infants and children, customarily have been individual pieces of furniture, fixed and unalterable in their construction and very limited in use. For example the infant rapidly outgrows the high-chair, or quickly becomes conscious of its difference from the chairs used by adults and resents it. In either event the use of a standard or adult chair is almost mandatory, and entails makeshift expedients to adapt it to the child. The best that can be said for such adaptations is that they raise the elevation of the child from the seat of the chair but, like the high-chair, no adjustment to the child is possible nor is any provision made to hold the infant or child in place. Moreover, the high-chair is comparatively expensive and comprises an extra article of furniture more or less unsightly and used only on occasion.

The present invention overcomes all of these manifest objections and inadequacies of the high-chair and of the expediently adapted standard chair by providing an auxiliary seat having a back by which this seat may be removably suspended from the back of a chair so as to be positioned above and approximately parallel to the seat of the chair. A tray is associated with the auxiliary seat and is capable of bodily adjustment toward and away from said back. All of the components are so arranged and associated that they may be folded one above the other to an overall thickness not materially greater than the combined thickness of the seat, tray and back and with a superficial area approximating that of the seat alone. Thus the present auxiliary seat may be stored in very little space or may be easily transported.

Referring to the drawings, the numeral 10 designates the seat of the collapsible, auxiliary chair of the present invention. This seat is a relatively flat, rigid member made of any suitable material, preferably wood. The width and front to rear depth of this seat are preferably somewhat less than the corresponding dimensions of the seat 11^a (Fig. 2) of the conventional or ordinary chair 11 with which the device of the present invention is associated so that when the seat 10 is in operative position above and parallel to the seat 11^a of the ordinary chair, the marginal portion of the seat 11^a may be used as a foot rest by the occupant of the auxiliary seat 10. A rigid L-shaped bracket, comprising a horizontal leg 12 and an upright substantially vertical leg 14, is

secured to each of the respective side edges of the seat 10 adjacent to the rear edge of the seat. The horizontal leg members 12 are secured to the edges of the seat 10 by means of screws 13 or equivalent fastening means. The upright legs 14 of the brackets project up above the upper surface of the seat to a distance exceeding the thickness of the tray, hereafter to be described. The lower part of the chair back 15 (which is preferably a unitary piece of wood) is interposed between the upstanding bracket members 14 and is pivotally connected to the brackets by pivot members 16. The aligned pivotal axes of the parts 16 are so spaced above the upper surface of the seat 10 that when the back is folded down to horizontal position substantially parallel with the seat, it is spaced above the upper surface of the seat a distance sufficient to permit the tray (hereafter described) to be interposed between the back and seat.

A rigid, elongate metallic guide member 17 is secured to each of the lateral edges of the back 15, these guide members 17 extending from a point near the top of the back down to a point approximately midway the height of the back. Throughout the major portion of its length each of these guide members 17 comprises a part which is spaced from the adjacent edge of the back (Fig. 1) and which is provided with an elongate guide slot 18 (Fig. 2). At each of its opposite ends the guide member 17 has a flat attaching portion which engages the edge of the back 15 and which receives a fastener member 19, for example a screw, whereby the guide member is rigidly secured to the back.

The upper extremity of each guide member is shaped to provide a vertically elongate socket 20 (Fig. 8) designed to receive the shank portion 21^a of a suspension hook 21, the shank portion having a head at its lower end which is received in an enlargement of the lower part of the socket whereby the hook is prevented from escaping from the socket. Each hook preferably consists of a length of stiff steel rod-stock, the straight shank portion being arranged within the socket 20 as above described, and the upper portion of the rod being bent twice, at right angles, to form a hook of such dimensions that it may be hooked over the upper edge of the back 11 of a conventional chair, thereby to suspend the auxiliary chair of the present invention in operative position, as shown in Fig. 2. Preferably the hook portion 21 which engages the back of the chair is padded, for example, by slipping a length of rubber tubing over the rod which forms the hook.

A rigid tray 22, of any suitable material and construction, for example wood, is adjustably associated with the seat and back. Desirably this tray is of somewhat less front to rear width than the seat, but, as here illustrated, it is of a transverse width somewhat greater than that of the back, thereby providing for the convenient attachment of the arms as hereafter described.

The tray is so connected to the seat that in all relative positions of the seat and tray they are disposed in substantially parallel planes. A preferred means for so connecting the tray and seat is by the use of a pair of substantially U-shaped members, preferably made of stiff steel rod-stock, each of these U-shaped members having a base portion 233 (Fig. 1) which is straight and which is disposed against the under surface of the tray (parallel to the front edge of the latter) and pivotally connected to the tray by means of bearing brackets 234 rigidly secured to the underside of

the tray. At each end of each base member 233 the rod material is bent at substantially right angles to form the parallel legs 23 of the U-shaped member. The free ends of these legs 23 are again bent, at right angles, to provide pintle elements having their axes aligned, and these inwardly directed pintle elements 235 are received in aligned socket openings in the opposite edges, respectively, of the seat member. The pairs of socket openings which thus receive the inwardly directed pintle portions of the two U-shaped members are spaced apart horizontally, as indicated at 236 and 237 (Fig. 2) while the bearing brackets 234 which receive the respective base portions of the two U-shaped members are spaced by the same distance from front to rear on the underside of the tray 22. With this arrangement the two legs 23 at each side, respectively, of the auxiliary chair constitute parallel links connecting the seat and tray, thus constraining the tray to remain parallel to the seat as it moves up and down toward and away from the seat. Since each of the U-shaped members is of stiff-substantially rigid material, with its legs 23 parallel and disposed in the same plane, the legs 23 of each U-shaped member are constrained to rock simultaneously and through the same arc, thus assuring a smooth motion without possibility of cocking or binding.

At each side of the auxiliary chair the tray is connected to the back by an arm of variable length. Preferably each arm comprises a hollow, rigid sleeve member 24, for example of sheet steel, here shown as substantially rectangular in vertical, transverse section (Fig. 6), and having a longitudinally extending slot 25 in its under face. At its rear end, each of these sleeve members is provided with an inwardly directed horizontal pivot pin 26 (Fig. 5) having a head which is located between the slotted portion of the guide 17 and the edge of the back, the shank of the pin sliding in the slot 18. Each arm also comprises a bar 27 (Fig. 6) which may, for example, be of wood, which is slidable telescopically within the corresponding sleeve member 24, and which is hinged at its forward end at 28 to the rear edge of the tray. The width of the tray exceeds that of the back sufficiently to permit the forward ends of bars 27 to be hinged directly to the rear edge of the tray. Thus, when the chair is folded, the arms may lie in the plane of the back at opposite edges of the latter. This sliding connection between the sleeve 24 and the bar 27 permits the tray to be moved bodily from front to rear relatively to the back. In order to hold the tray in adjusted position, provision is made for locking the bar 27 at any of a series of predetermined positions relative to the sleeve 24. As shown in Fig. 7, the bar 27 is provided with a central, longitudinal groove 32 in its underside which is aligned or registered with the slot 25 in the underside of the sleeve 24. A latch bar 29 (Figs. 5 and 7) is arranged within the groove 32 of the bar 27 and is pivotally connected to the bar 27 by a horizontal pin 30 (Fig. 5) adjacent to the forward end of the bar 27. This latch bar 29 is preferably of stiff sheet metal of a vertical depth such that its lower edge normally projects down below the lower surface of the sleeve 24 when the parts are assembled. This latch bar 29 is provided at its rear end with a right-angular portion 31 (Fig. 5) which constitutes a locking tooth, the upper part of which is normally housed in a chamber 36 (Fig. 6) in the underside of the bar 27 at the rear end of the slot 25. A coiled spring 33 (Fig. 7) housed within a socket in the bar 27

urges the forward end of the latch bar 29 downwardly, the forward end of the latch bar adjacent to the spring constituting a fingerpiece to which upward pressure may be applied for swinging the latch bar so as to move its rear end downwardly. Bordering the slot 25, the sleeve 24 is provided with a series of spaced notches or recesses 35 (Fig. 5) designed for selective engagement by the locking tooth 31. In any selected adjusted position of the bar 27, relative to the sleeve 24, the chamber 36 of the bar approximately registers with one or another of the recesses or notches 35, and the tooth 31 is engaged within said notch or recess. The latch bar 29 moves bodily with the bar 27 when the latter is adjusted relatively to the sleeve 24, but such movement is only possible when the forward end of the bar 29 has been moved upwardly in opposition to the spring 33 sufficiently to disengage the tooth 31 from the retaining notch or recess 35. When the teeth of the two latch bars have been disengaged from the recesses 35, the bars 27 may be moved forwardly or rearwardly within the sleeves 24, thus bodily moving the tray from front to rear. When properly adjusted, release of the latch bars permits their teeth to enter recesses 35, thus rigidly holding the arms at adjusted length and retaining the tray with its rear edge at the desired distance from the forward face of the back.

To prevent the bar 27 from being withdrawn completely from the sleeve 24 and to arrest and limit its forward movement, a stop 34 (Fig. 5) is provided, projecting downwardly from the recessed portion of the sleeve 24, this stop being contacted by the tooth 31 when the tooth is in position to be received by the foremost recess 35. Whether or not the tooth actually enters said recess, the tooth will engage the stop 34, thus preventing over-travel of the bar 27 in a forward direction.

As illustrated, a locking toggle may be arranged at each side of the chair structure. Each toggle comprises a link 37 pivoted to one side edge of the seat 10, and a cooperating link 38 pivoted to the edge of the back, preferably at the lower end of the guide 17. The toggle links 37 and 38 are provided at their proximate ends with angular extensions 39 which are pivotally connected at 40. When the links 37 and 38 are aligned, the extensions 39 overlie one another, but when the chair is collapsed (Fig. 4), the link 37 is parallel to the edge of the seat 10 while the link 38 is parallel to the back 15 and the extensions 39 are substantially aligned with each other. However, as illustrated in Fig. 4, the spacing of the folded seat and back is such, by reason of the height of the bracket members 14, that there is ample room for the aligned extensions 39 and for the location of the tray between the seat and back.

If, with the parts in the collapsed position shown in Fig. 4, it be desired to set the chair structure up in operative position, as shown in Fig. 2, the user will first grasp the upper portion of the back and swing the latter to the upright position. He then grasps the tray near its opposite lateral edges and lifts the latter directly up. During the first portion of this movement, the pivot pins 26 at the rear ends of the sleeves 24 move up along the slots 18 in the guides 17, this upward movement continuing until, as diagrammatically illustrated in Fig. 9, the included angle A between the upper surface of the tray 22 and the arm 24 substantially equals

the included angle A' between the forward face of the back 15 and the arm 24. Further upward movement of the tray is accompanied by a downward movement of the pivot pins 26 in the slots 18, this downward movement continuing until the pivot pins have reached the lower ends of the slots. The slots are of such length that when the pivot pins are in the lower ends of the slots, the arms are approximately horizontal. Since the arms swing about the horizontal axes of the hinges 28, the weight of the arm tends to hold the pivot pin 26 at the lower end of the slot. Since collapse of the device, after it has once been set up, can only take place by upward movement of the pins in the slots 18, it is manifest that the parts are substantially locked in position when the pins are in the lower ends of the slots. Rearward movement of the tray is directly opposed by the reaction of the pin 26 against the rear wall of the slot 18, and such slight component of upward force as there may be, due to any slight upward inclination of the arm, is opposed by the friction of the pin in the slot.

The toggle linkage, comprising the parts 37 and 38, locks the chair against accidental collapse since, in the set up condition of the device, the pivotal axis at 40 lies slightly forward of a line joining the pivotal connections between the remote ends of the links 37 and 38 with the seat and back, respectively. Although a toggle device has here been shown by way of example as a convenient means to hold the seat and back in operative relation of use, it is obvious that other and equivalent conventional locking means, such as a set screw or latch, may be employed.

After the chair has been set up, the tray may be moved from front to rear (after first disengaging the teeth 31 from notches 35) so as to adjust the spacing between the back and the rear edge of the tray to correspond to the size of the child occupying the chair.

While the device as thus described is particularly intended as shown for suspension from the back of an ordinary conventional chair, it is manifest that it may be set down onto the chair seat if desired, or suspended from some other support. For example, it may be suspended from the back of the seat of a motor vehicle and, if intended for such use, it is manifest that the hooks 21 will be made of appropriate size to engage a seat back of greater thickness than that shown herein.

One desirable embodiment of the invention has been shown by way of example, but it is to be understood that the invention is broadly inclusive of any and all modifications falling within the scope of the appended claims.

What is claimed is:

1. In combination, in a device of the class described, a seat member, rigid brackets fixedly secured to opposite side edges, respectively, of the seat member, each bracket comprising a portion projecting upwardly above the upper surface of the seat, a back interposed between the upwardly projecting portions of the brackets and pivotally connected to said brackets to swing to and from a position substantially parallel to and spaced from said seat member, a tray, parallel links interposed between each side of the tray and the corresponding side of the seat member and pivoted at their ends respectively to the tray and seat member whereby the tray may move relative to, while being maintained parallel to, the seat member, and extensible arms interposed between and

hinged at their ends respectively to the tray and to the back, the hinge axis at the rear end of each arm being slideable upwardly along the edge of the back from normal position to permit folding the back downwardly, and releasable locking means for holding the back and seat in the relative positions of use.

2. In combination, in a device of the class described, a seat member, a rigid bracket fixedly secured to each of the opposite side edges, respectively, of the seat member, each bracket comprising a portion which extends above the upper surface of the seat member, a back interposed between said upwardly projecting portions of the brackets, pivot means securing the back to said brackets so that the back may swing about a horizontal axis to and from a position substantially parallel to and spaced from said seat member, a tray, parallel links connecting the tray and the seat member whereby the tray may move toward and away from the seat member and will always remain substantially parallel to the seat, extensible arms hinged at their forward ends to the rear edge of the tray, and a sliding, pivotal connection between the rear end of each arm and the back, and releasable locking means for holding the back and seat in the relative position of use.

3. In combination, in a device of the class described, a seat member, a back hinged to the seat member to swing to and from a position substantially parallel to and spaced from said seat member, a tray, the pivotal axis about which the back swings being horizontal and spaced above the upper surface of the seat a distance such that when the back is folded down into parallel relation to the seat it is spaced above the upper surface of the seat a distance sufficient to accommodate the tray between the back and seat, parallel links connecting the tray and seat member whereby the tray may move toward and away from the seat member and will always remain substantially parallel to the latter, arms connecting the tray and back, each arm comprising two relatively telescopic members whereby the length of each arm may be varied thereby permitting bodily adjustment of the tray from front to rear, the forward member of each arm being hinged to the tray and the rear end of each arm being provided with a pivot which connects it to the edge of the back, the back being provided with guide means for the pivots whereby the latter may move up and down along the edges of the back.

4. The combination with a seat member, of brackets fixedly secured to the seat member and having portions which project above the upper surface of the seat member in alignment one with the other transversely of the seat member, a back pivoted between the projecting portions of said brackets to swing to and from a position where it is substantially perpendicular to the seat to a position where it is substantially parallel to but spaced from the seat member, releasable means for holding the back and seat in the normal operative position of use, a tray, parallel links permanently connecting the seat and tray whereby the tray may move toward and away from the seat member and the back and will always remain substantially parallel to the seat member, arms comprising telescopic portions connecting the back and tray, said arms being pivoted at opposite ends to the tray and back respectively, the axis of the pivotal connection between the rear end of each arm and the back being slideable upwardly from normal position along the edge

of the back to permit folding the back downwardly, the lengths of the arms varying as the position of the tray is changed, relatively to the back, and means for locking the telescopic portions of the respective arms in desired position of adjustment.

5. The combination with a seat member, of a back to cooperate therewith, means for hinging the back to the seat member to occupy a position substantially at right angles thereto, or in the alternative a position parallel to and spaced from the seat member, a tray positioned approximately parallel to the seat member, parallel links interposed between and pivoted to the seat member and the tray to support the latter for movement toward and away from the former and to maintain the tray substantially parallel to the seat member during said movement, whereby the tray may be positioned approximately flush against the seat member between it and the back, variable length arms interposed between and pivoted at their ends to the tray and back to rest in the plane of the back when the latter rests parallel to the seat member, the axis of the pivotal connection between the rear end of each arm and the back being slideable upwardly from normal position along the edge of the back to permit folding the back downwardly, and a toggle interposed between the back and the seat member with the pivot between its arms off-set laterally to permit one arm to rest in the plane of the back and the other arm to rest in the plane of the seat member when the back and the seat member are parallel one to the other as aforesaid.

35. 6. The combination with a seat member, of a pair of aligned brackets fixed to the seat and having portions which project above the upper surface thereof adjacent one of its edges, a back hinged between the projecting portions of said brackets to swing from a substantially vertical position to a position spaced from and substantially parallel to the seat member and vice versa, means for locking the back and seat in the relative, operative position of use, a tray, a pair of parallel links pivoted to and interposed between end portions of the seat member and tray to support the tray at all times parallel to the seat member and permit its movement toward and away from the seat member, a bar hinged to each side of the tray, a sleeve slidably pivoted to each side of the back to reciprocatingly receive the aligned bar therein, and a disengageable lock associated with each bar and sleeve to releasably and selectively secure the bar to the sleeve.

55. 7. The combination with a seat member, of a pair of brackets fixed to the seat having portions which project above the upper surface thereof adjacent one of its edges, a back hinged between the projecting portions of said brackets to swing from a substantially vertical position to a position spaced from and substantially parallel to the seat member and vice versa, means for locking the back and seat in the relative, operative position of use, a tray, a pair of parallel links pivoted to and interposed between end portions of the seat member and tray to support the tray at all times parallel to the seat member and provide for its movement toward and away from the seat member, a bar hinged to each side of the tray, a sleeve slidably pivoted to each side of the back to reciprocatingly receive the aligned bar therein, a lock associated with each bar and sleeve to releasably and selectively secure the bar against reciprocating movement relative to the sleeve, and a pair of toggle arms on each side of the assembly,

one pivoted to the seat member and the companion arm to the back, the adjoining end portions of said arms being angularly offset with the extremities of said offset portions being connected pivotally one to the other.

8. A collapsible chair comprising a seat, a back and a tray, hinge means uniting the seat and back, releasable means operative to hold the seat in normal position substantially at right angles to the back, extensible arms connecting the tray and back, each arm being hinged at its front end to the tray and being pivotally connected at its rear end to the back, the axis of the pivotal connection between the rear end of each arm and the back being slidably upwardly from normal position along the edge of the back to permit folding the back downwardly, parallel links pivotally connected to the seat, corresponding links of the respective pairs constituting the parallel legs of a rigid, unitary U-shaped piece, the bases of the two U-shaped pieces being spaced apart and parallel to the front edge of the seat, and means pivotally and permanently uniting each of said bases to the tray.

9. A collapsible chair comprising a seat, a back and a tray, means permanently connecting the tray to the back, said means comprising extensible arms, each arm being hinged at its forward end to the tray and being pivotally connected at its rear end to the back, the axis of the pivotal connection between the rear end of each arm and the back being slidably upwardly from normal position along the edge of the back to permit folding the back downwardly, hinge means permanently uniting the seat and back, parallel links pivotally connecting the seat and tray, and means rigidly connecting a link of one pair to the corresponding link of the other pair whereby the connected links are constrained to move in parallel planes, each link being so pivotally united to the tray as to rock about an axis parallel to the forward edge of the seat.

10. A collapsible chair comprising a seat, a back, a tray, means permanently connecting the tray to the back, said means comprising extensible arms each hinged at its forward end to the tray and each pivotally connected at its rear end to the back, the axis of the pivotal connection between the rear end of each arm and the back being slidably longitudinally of the edge of the back, hinge means uniting the seat and back, a pair of parallel links arranged at each side of the seat, means pivotally and permanently connecting the upper end of each link to the tray, the lower ends of the links rocking about axes extending transversely of the seat, and means constraining corresponding links of the respective pairs to rock through the same arc.

11. A collapsible chair comprising a seat, a back, a tray, parallel links connecting the tray and seat, hinge means connecting the back and seat, and telescopically extensible arms connecting the tray to the back, the arms being hinged at their forward ends to the tray, pivot means connecting the rear end of each arm to the back, the axis of the pivotal connection between the rear end of each arm and the back being slidably longitudinally of the edge of the back, the links supporting the tray for movement from front to rear.

12. A collapsible chair comprising a seat, a back, a tray, parallel links connecting the tray and seat, and hinge means connecting the back

and seat, releasable means operative to hold the seat substantially at right angles to the back, said links supporting the tray for movement from front to rear, a pair of hollow arms, each arm being hinged at its rear end to the back, the hinge axis at the rear end of each arm being slidably longitudinally of the edge of the back, a bar slidably within each hollow arm, hinge means connecting the forward end of each bar to the tray, and latch means for holding each bar in selected position of adjustment within its respective hollow arm.

13. A collapsible chair comprising a seat, a back, a tray, hinge means connecting the back and seat releasable means operative to hold the seat substantially at right angles to the back, parallel links supporting the tray so that the latter is capable of movement from front to rear while always remaining parallel to the chair bottom, a pair of telescopically extensible arms, each arm being hinged at its forward end to the tray and at its rear end to the back, the hinge axis of the rear end of each arm being slidably longitudinally of the edge of the back, the tray being movable bodily from front to rear relatively to the back without disconnecting the tray from the arms.

14. A collapsible chair comprising a seat, a back and a tray, hinge means connecting the back and seat releasable means operative to hold the seat substantially at right angles to the back, arms hinged to the rear edge of the tray, pivot means connecting the rear ends of the arms to the seat back, the pivot means being slidable longitudinally of the back, the seat and tray normally being parallel and spaced apart and substantially perpendicular to the back, and parallel links connecting the seat and tray, whereby the tray is movable downwardly from its normal position to a position where it is close to and parallel with the seat, and the back being movable to a position closely parallel to and above the tray.

15. A collapsible chair comprising a seat, a back and a tray, hinge means uniting the seat and back, releasable means operative to hold the seat substantially at right angles to the back, parallel links connecting the seat and tray and constraining the tray to remain parallel to the seat at all times, arms hinged at their forward ends to the rear edge of the tray, the rear ends of the arms having studs which slide in elongate slots at the opposite edges of the back, said studs normally being positioned adjacent to the lower ends of said slots, the chair being collapsible by moving the studs upwardly along the slots until the angle between the arms and tray is substantially equal to the angle between the arms and back, and then moving the studs downwardly until the back is substantially parallel to the seat and tray.

ALFRED Z. BOYAJIAN.
